UNITED STATES PATENT OFFICE.

ELVIN H. JOHNSON, OF WINNETKA, ILLINOIS, ASSIGNOR TO GLYNN-JOHNSON, INC.
A CORPORATION OF DELAWARE.

DESIGN FOR A DOORSTOP.

Application filed February 9, 1927. Serial No. 20,662. Term of patent 14 years.

To all whom it may concern:

Be it known that I, ELVIN H. JOHNSON, a citizen of the United States, and a resident of Winnetka, in the county of Cook and State of Illinois, have invented a new, original, and ornamental Design for Doorstops, of which the following is a specification.

In the accompanying drawings:

when the stop is holding the door open; and

Figure 2 is a plan view looking downward on the complete stop when the arm is swung up into inoperative position.

I claim:

The ornamental design for a doorstop, as shown and described.

In testimony whereof, I have signed my name to this specification.

ELVIN H. JOHNSON.
